UNITED STATES PATENT OFFICE.

JOSEF MATEJEC, OF PRAGUE, BOHEMIA, AUSTRIA-HUNGARY.

GLOVE-PUNCH.

SPECIFICATION forming part of Letters Patent No. 423,526, dated March 18, 1890.

Application filed June 20, 1889. Serial No. 314,897. (No model.)

To all whom it may concern:

Be it known that I, JOSEF MATEJEC, a subject of the Emperor of Austria, residing at Prague-Zizkow, Bohemia, Austria-Hungary, have invented certain new and useful Improvements in Punches for Tambouring Leather Gloves, of which the following is a specification.

My invention relates to an improved punch 10 for punching the leather of gloves to be tamboured with silk thread, pearls, coral, or other materials. With the punches hitherto in use only straight rows of holes could be produced.

15 The improved punch of my invention has for its object to punch the holes in rows of any curved, angular, or other convenient shape or design.

20 The invention consists in the various features of improvement more fully pointed out in the claim.

Before describing the details of construction, I desire to say that I am well aware that machines carrying peg-awls have been used 25 for punching holes in shoe-soles. In one instance a wooden stock has been used in connection with a securing-plate, the plate having apertures for the passage of the points of the awls, and such apertures have been shou- 30 dered, so as to receive an awl having a cylindrical pointed portion and a head or shou- dered portion. This form of device would be very objectionable for the purposes of my invention. In another instance a stock has 35 been provided with peg-awls for punching shoe-soles, and a guide-plate through which the awls pass secured to the stock-plate by bolts in such a manner that the outer plate will serve as a pressure-plate in drawing the 40 needles from the soles after being punched, springs being interposed between the face-plate and stock. This device is objection- 45 able, inasmuch as the needles which I employ are of a very delicate character, differing ma- terially from peg-awls, and springs, if used, would in many cases cause a lateral strain upon the needles which would impair their usefulness and destroy the design for the tambouring.

50 In the accompanying drawings, Figure 1 is

a bottom view of my improved punch. Fig. 2 is a vertical cross-section thereof, and Fig. 3 a vertical longitudinal section thereof.

The stamping-plate *a* of the punch is made of brass, steel, or other metal, and is some- 55 what wider and longer than the design to be produced. It should be of sufficient height to afford a strong hold for the punching-needles *b*, secured within the plate. Small holes are bored through plate *a* at little dis- 60 tances from each other along the lines of the design to be produced. Into these holes the punching-needles of a slightly-tapering shape are forced, projecting downward from the lower or working surface of plate *a*. As these 65 needles must be placed very close to one another for the purpose of properly punching the glove, they are made headless, or of uniform taper from end to end. By their tapering form they are prevented from falling out 70 of their seats. The plate *a*, when provided with the needles *b*, is firmly secured to a plate *c* of corresponding size and shape, integral with or secured to the handle *d* of the tool. The plates *a* and *c* are connected by screw- 75 bolts *f*. An intermediate plate of steel or hard metal *e* may be interposed between the plates *a* *c* to prevent the needles from being forced into plate *c*, should the latter be formed out of a soft material. 80

The plate *a* may be readily removed from the plate *c* and exchanged for another punching-plate carrying the punching-needles ar- ranged to form a different design.

The operation of punching the holes into 85 the leather by means of this improved punch- tool is the same as hitherto practiced with the ordinary punch. The needles *b* might, according to a modification of my invention, be as well secured within the upper plate *c*. 90 In this case the lower plate *a* would contain needle-holes corresponding to the rows of needles on the plate *c* to afford passage to the needle-points.

What I claim is— 95

The improved punch for gloves described, consisting, essentially, of the plate *c*, having the integral handle *d* and the apertures for the passage of bolts, the perforated plate *a*, also having apertures to receive said bolts, 100

the headless tapering needles, as distinguishable from peg-awls, the hard-metal plate *e*, backing said needles and interposed between the plates *a* and *c*, and the bolts *f*, passing 5 through both plates *a* and *c* and carrying nuts at their upper ends, whereby the parts may be readily removed and adjusted, substantially as specified.

In testimony whereof I hereunto sign my name, in the presence of two subscribing witnesses, this 25th day of May, 1889.

JOSEF MATEJEC.
